UNITED STATES PATENT OFFICE

SERENUS H. A. YOUNG, OF ST. PAUL, MINNESOTA

DESIGN FOR A FRUIT JUICER

Application filed November 14, 1932. Serial No. 45,968. Term of patent 3½ years.

To all whom it may concern:

Be it known that I, SERENUS H. A. YOUNG, juicer, showing my new design. a citizen of the United States, residing at St. Paul, county of Ramsey and State of Minnesota, have invented a new, original, and ornamental Design for a Fruit Juicer, of which the following is a specification, reference being had to the accompanying drawing, forming part thereof,

Figure 1 is a perspective view of the fruit juicer, showing my new design.

Figure 2 is a top plan view of the same.

I claim:

The ornamental design for a fruit juicer substantially as shown.

SERENUS H. A. YOUNG.
